CLAIM

The ornamental design for an agitation device, as shown and described.

DESCRIPTION

FIG. 1 is a top perspective view of an agitation device showing the new design.

FIG. 2 is a bottom perspective view of the agitation device.

FIG. 3 is a side view of the agitation device.

FIG. 4 is another side view of the agitation device.

FIG. 5 is a top plan view of the agitation device; and,

FIG. 6 is a bottom view of the agitation device.

The broken lines shown in the Figures are used for illustrative purposes only and form no part of the claimed design.
